UNITED STATES PATENT OFFICE

2,538,691

VOICE COIL FOR RADIO LOUD-SPEAKERS

Richard K. Y. Kim, Honolulu, Territory of Hawaii

Application July 19, 1948, Serial No. 39,472

1 Claim. (Cl. 179—115.5)

1
This invention relates to loud speakers.

An object of this invention is to provide in a loud speaker of that type embodying a vibratory diaphragm or cone which will practically eliminate inherent distortion and at the same time provide high power handling capacity.

Another object of this invention is to provide in a loud speaker, a vibratory diaphragm or cone wherein the reflected impedance to the line or tubes will be negligible, the frequency response will be improved, and the bass and treble overtones which were heretofore lost or distorted will be made audible and free from distortion.

A further object of this invention is to provide an improved loud speaker wherein the response is linear with input over the entire audio frequency range.

With the above and other objects in view, my invention consists in the arrangement, combination and details of construction disclosed in the drawings and specification, and then more particularly pointed out in the appended claim.

In the drawing:

Figure 1 is a fragmentary vertical section of a loud speaker embodying this invention;

Figure 2 is a fragmentary sectional view taken on the line 2—2 of Figure 1.

Referring to the drawing, the numeral 10 designates generally a loud speaker which includes an electro-magnetic member 11 having an iron core 12 extending therefrom and projecting loosely into an opening 13 which is formed in a plate 14. A cone or diaphragm 15 is supported by flexible supporting means 16 from the plate 14 and includes a cylindrical central tubular portion 17 projecting loosely into the opening 13 and engaging loosely about the iron core 12.

The tubular member 17 has wound thereabout a coil 18 and there is interposed between the coil 18 and the outer surface of the tubular member 17 a metallic film or coating 19. This film or coating 19 is formed of powdered iron and as shown in Figure 1 the coating 19 extends under the entire length of the coil 18.

A second metallic coating or film 20 is disposed about the outer surface of the coil 18 and also terminates at a point forwardly from the rear end of this coil. The outer coating 20 is of such thickness that there will be maintained an air gap or space 21 between the coating 20 and the wall of the opening 13. The two coatings 19 and 20 are connected together by a connecting coating 22, and the connected coatings have the effect of creating a high magnetic flux density area adjacent the voice coil 18 for the currents of the voice coil to react on. These coatings also

2
compensate for the difference in magnetic densities with respect to the front and rear, because in uncoated speakers the magnetic densities are usually greater at the rear. The coil 18 is commonly known as the voice coil and is disposed in the magnetic flux generated between the core member 12 and the plate 14. With a voice coil having a partial coating and lining as hereinbefore described, the loud speaker will have a higher degree of efficiency with negligible inherent distortion and the power handling capacity of the speaker will be higher. Furthermore, the reflected impedances will be negligible to the line or tubes and there will be a better or increased frequency response, particularly in the bass overtones and the treble overtones which have heretofore either been lost or distorted.

The term "diaphragm" as herein set forth and claimed will include both a diaphragm member and a cone which is supported from a flexible support so that the cone will be subjected to the vibrations caused in operation of the loud speaker.

I do not mean to confine myself to the exact details of construction herein disclosed but claim all variations falling within the purview of the appended claim.

What I claim is:

In a loud speaker having an electro-magnetic member, an electro-magnetic core extending therefrom, with an apertured plate about a portion of the core and a diaphragm extending from said plate having a cylindrical central portion projecting into the aperture in said plate about said coil, a voice coil wound about said central portion within said aperture, a powdered iron film interspersed between the inner side of said coil and said central portion, a second powdered iron film surrounding only a portion of the outside of said coil, said portion being of less than one half the length of the coil at the end thereof remote from the electro-magnetic member, and a connecting film between the edges of said first and second film over one end of said coil.
